UNITED STATES PATENT OFFICE.

F. M. STRONG AND THOS. ROSS, OF BRANDON, VERMONT, ASSIGNEES TO
JOHN HOWE, JR., OF THE SAME PLACE.

IMPROVEMENT IN PLATFORM-SCALES.

Specification forming part of Letters Patent No. 55,963, dated June 26, 1866.

To all whom it may concern:

Be it known that we, FRANCIS M. STRONG and THOMAS ROSS, of Brandon, in the county of Rutland and State of Vermont, have made new and useful Improvements in Platform-Scales; and we do hereby declare the following to be a full, clear, and exact description of the nature, construction, and operation of the same, sufficient to enable one skilled in the art to which it appertains to construct and use the same, reference being had to the accompanying drawings, which are made part of this specification, and in which—

Figure 1 is a plan or top view, the weigh-box being sectioned on the line $y y$, Fig. 2. Fig. 2 is an elevation of that part of the machine containing the weigh-box and looking in the direction of arrow 1 from the section-line $x x$, Fig. 1. Fig. 3 is an elevation of the platform portion from the section-line $x x$, Fig. 1, looking in the direction of arrow 2. Fig. 4 is a vertical section of the weigh-box on line $z z$, Fig. 2. Fig. 5 is an elevation of that portion of the apparatus to which the light ends of the main levers are connected.

The same letters refer to like parts in the different figures.

The invention consists in the construction of the bearers upon which the platform is imposed; in the construction of the compound link by which the light end of the main levers are connected with the arm on one end of the extensible rod which connects the levers at the platform with the levers in the weigh-box; in the extensible rod which connects the works at the platform with works in the weigh-box and which admits of the scale being adapted to variations of distance between the two; in the method of operating the poise from the outside of the weigh-box, and of indicating by stop-pieces on a graduated scale the determinate position for the poise-shifter.

A A is the platform, which is supported at its four corners by that number of bearers on two shafts, B B. To these rocking arms are attached levers C C, whose light ends are mutually linked to the secondary lever D, which conveys the power toward the scale-beam.

The bearers are counterparts of each other, and one supports each corner of the platform.

G is the base or sill, and under each corner of the platform is a block, H, which has bearings for the edges a of the shafts B, while the upwardly-projecting edges b of the shafts support a T-shaped bearing, c, across the upper surface of which are depressions containing rollers d d, which latter support a plate, e, whose under side has corresponding depressions which fit upon the rollers. On the upper side of the plate e is a similar concave, but at right angles to the former ones, and this is occupied by a roller, f, which supports the shoe h under the platform-timbers. By this arrangement the platform has a longitudinal movement on the rolls d d and a lateral one on the rolls f, and that without producing any motion in the bearing c, which might be injurious to the knife-edges which support it.

By the means described the weight of the platform and its load, if it has one, is thrown upon the shafts at points inside of their bearings at a , and the levers C being depressed by the weight, their light ends are caused to set in motion the train of levers which are eventually connected to the scale-beam, and which I shall proceed to notice.

At the light ends of the lever C are bearing-edges i, which rest within the loop j of the links k, the upper ends of the said links having loops l, which rest upon a bearing, m, which is supported upon the secondary lever D, above spoken of. The lever D is of a horse-shoe shape, and is supported at one end by hangers n n from a bracket, o, which rises from the sill G, and at its other end is supported by a link, p, and suitable bearing-edges from one end of the arm E, which is fastened upon the shaft F and supported at its other end by a link from a pillar, q, which rises from the sill G.

Each end of the shaft F has a lever-arm of similar character, the one E, the nearest to the platform, having been described. The other arm, E', is suspended by links and rod r from the scale-beam N, while its other end is attached by a rod and hook, L, to the sill of the weigh-frame M. The arms E and E', or one of them, are adjustable on the shaft F, so that the weigh-frame M may be set nearer to or farther from the platform, according to the convenience or necessities of the case.

The portion of the apparatus consisting of the shaft F and its arms E E' is suspended at two points from the pillar q, and the scale-beam K, at another point, is attached to the floor at L, and at another point to the secondary lever D, whose motions cause the said portion F E E' to vibrate on the said points q and L; and as the arms E E' are of equal length, the same effect is communicated to the scale-beam at the point of connection with T as is communicated from the secondary lever D.

The links k, which connect the bearings on the levers C C and D, are flaring, so as to have a wider upper bearing, and this so that the links k may stand inclined in opposite directions; and if from any cause the position of the levers should become deranged, one would be more nearly perpendicular while the other was less so, and would compensate for the derangement.

The weigh-frame M has a box inclosing the scale-beam N, and the door or lid O is shown raised in Fig. 2.

The beam is graduated with notches cut to any desired subdivision of weight. The poise s is suspended from these notches by a link with an oblong opening to receive the beam. This link is rigidly secured to and forms part of the poise, and has the upper end of the opening formed into a knife-edge to rest in the notches.

On either side of the poise are lugs t, to rest in the notches of the compound lever P, by which it is raised from the beam and moved from point to point. The lever is slipped on the rod Q by the handles, which project through an opening in the weigh-box for that purpose.

On the inner side of the lid O is a slotted plate, u, graduated to correspond exactly with the graduations on the scale-beam. On the plate u are notched stop-pieces w, secured by screw-bolts from the inside. The number of stop-pieces w, in case of its use as a charging-

scale for a blast-furnace, would correspond with the number of different materials making the charge, and each one should be marked with the name of the material it represents—say, for instance, coal, ore, and the different fluxes used.

In use it is designed that the superintendent of the work shall set the stop-pieces to the graduations on the plate indicating the weight desired of each. He then closes and locks the lid O, thereby securing the stop-pieces from change. The projection on the trigger x of the lever P rests in the notches of the stops w when the poise is supported from the corresponding notch of the scale-beam.

The equilibrium of the beam is indicated by the rod y, which is a prolongation of the loop at the point of the scale-beam, and, passing up through the top of the box, is terminated by a cross-piece, which is exposed to view, but protected from injury by a guard.

The construction and operation of the machine have thus been described in good faith; but trifling alterations may, of course, be made in it without departing from the principle of its construction.

What we claim therein as new, and desire to secure by Letters Patent, is—

1. The combination of the levers C C and the links k, with their upper and lower bearings, m i, and the secondary lever D.

2. The shaft F, in combination with the adjustable arms E E', as and for the purpose described.

3. The combination of the poise s, lever P x, graduated plate u, and movable stop-pieces w, as and for the purpose described.

FRANCIS M. STRONG. [L. S.]
THOMAS ROSS. [L. S.]
